COMBINED SHELF UNIT AND GAME DISPLAY PANEL

Frederick A. Hurley, 1204 Ali Baba Ave.,
Opa Locka, Fla. 33054

Filed Aug. 4, 1970, Ser. No. 24,301

Term of patent 14 years

Int. Cl. D6—04

U.S. Cl. D6—130

The figure on the drawing is a perspective view of the front, top and left side of a combined shelf unit and game display panel showing my new design, the outer surfaces of the back, bottom and right side thereof being planar and unornamented.

I claim:

The ornamental design for a combined shelf unit and game display panel, as shown and described.
